MILK HOLDING TANK

Edward L. Valentine, 3470 Randolph St.,
Huntington Park, Calif.

Filed Oct. 13, 1961, Ser. No. 67,071

Term of patent 14 years

(Cl. D23—1)

Fig. 3

The essential features of the design reside in the portions shown in full lines.

I claim:

The ornamental design for a milk holding tank, substantially as shown and described.
